UNITED STATES PATENT OFFICE.

PERCIVAL W. ELLIOTT, OF READING, ASSIGNOR TO THE HIGHLAND
FOUNDRY COMPANY, OF BOSTON, MASSACHUSETTS.

HEATING-FURNACE.

SPECIFICATION forming part of Letters Patent No. 552,055, dated December 24, 1895.

Application filed July 30, 1894. Serial No. 518,907. (No model.)

To all whom it may concern:

Be it known that I, PERCIVAL W. ELLIOTT, a citizen of the United States, residing at Reading, in the county of Middlesex and State 5 of Massachusetts, have invented a new and useful Improvement in Heating-Furnaces, of which the following is a full, clear, and exact description, reference being had to the accompanying drawings, forming a part of this 10 specification, in explaining its nature.

The invention relates to the herein-described improvement in heating-furnaces, whereby a volume of air preferably taken from the cold-air inlet is independently highly heated in a chamber in the upper part of the combustion-chamber, and then mingled with the heated air in the upper part of the usual heating-chamber, from whence it is distributed by means of the usual distributing-pipes, the object 15 of the invention being to increase the heating capacity of the furnace and also to increase its circulating power, and to prevent the formation in any part of the usual heating-chamber of dead-air spaces, the introduction 20 of the more highly heated air into the upper part of the heating-chamber employing or causing a more rapid circulation of the heat 25 in it and from it than would otherwise occur.

In the drawings, Figure 1 is a view principally in vertical central section upon the dotted line xx of Fig. 2 of a heating-furnace having the features of my invention. Fig. 2 is a view principally in horizontal section upon the dotted line yy of Fig. 1.

35 A is the ash-pit of the furnace; B, the firepot; C, the combustion-chamber; D, the outer casing or shell, and E the usual air-heating chamber. In the upper part of the combustion-chamber C is the customary air-heating 40 chamber F. This is preferably formed by the circular casting f , the cavity of which forms the heating-chamber, and which casting has radiating from it and integral therewith the tubular sections f' , each tubular section having an enlargement f^2 and flange f^3 , which bears against the inner surface of the combustion-chamber wall and is secured thereto by bolts or rivets which pass through holes therein, and the flange f^4 of the exterior flanged collar f^5 , the sleeve of the collar entering a hole 45 in the wall of the combustion-chamber, and the enlargement of the tube f' . (See Fig. 1.) One

of these radiating tubes forms the inlet-passage G and the others the outlet-passages H. The inlet-passage G has a collar f^5 , which is 55 also provided with an outward pipe-holding section to receive the upper end of a pipe f^7 , which extends from the cold-air inlet f^8 and provides means whereby the cold air is drawn or taken from the inlet. The outlets H open 60 into the heating-chamber E.

The operation of the device is as follows: The cold or outer air is supplied the main heating-chamber E and the heating-chamber F by means of the inlet or cold-air supply f^8 , the 65 air for the supply of the heating-chamber F passing through the pipe f^7 to it from the source of supply, the said pipe preferably being within the outer casing D of the furnace or in the hot-air chamber, but not necessarily 70 so. The air thus introduced into the chamber F circulates through it, is very highly heated therein and is expelled with considerable force into the upper part of the air-heating chamber through the outlets H, and thereby 75 prevents the air in the upper part of the chamber from becoming dead and causes sufficient increase in the air-pressure to produce a better circulation from the heating-chamber through the usual conducting-pipes, and also 80 adds to the heating capacity of the furnace.

While I prefer the form of auxiliary heating-chamber shown, because of its cheapness of construction and application and its great heating power, yet I do not confine myself to 85 the especial type described, so far as the principal features of my invention are concerned.

Having thus fully described my invention, I claim and desire to secure by Letters Patent of the United States—

90 The combination in a heating furnace of the combustion chamber C circular in shape, the heating chamber E surrounding the combustion chamber and the auxiliary heating chamber F, formed of a circular casting, placed in 95 the top of the combustion chamber near its wall, having a direct connection with the outer air and connected with the main heating chamber E by the outlets H, as and for the purposes described.

PERCIVAL W. ELLIOTT.
